DANIEL H. CHASON, OF ELIZABETH, NEW JERSEY, ASSIGNOR TO THE SINGER MANUFACTURING COMPANY, OF ELIZABETH, NEW JERSEY, A CORPORATION OF NEW JERSEY

SEWING-MACHINE-MOTOR CONTROLLER

Application filed December 16, 1927. Serial No. 240,587.

In the widespread application of electricity to the various arts, the sewing machine has received its share of attention, and various devices for the electric drive and control of 5 sewing machines have been made and used. While the growing demand is for the complete, factory equipped, electric sewing machine, there are in use large numbers of treadle-driven sewing machines which only 10 await the advent of a conveniently applicable and usable form of motor and motor-controller to convert them into electric machines. There has already been provided a 15 sewing machine motor adapted for attachment to the well-known family sewing machine so as to become, in effect, a permanent fixture or part of the machine, not requiring to be removed or shifted when the machine is to be put away or made ready for use. I refer 20 to the electric sewing machine described in the U. S. patent to Diehl and Hemleb No. 1,488,234 of March 25, 1924.

The usual sewing machine motor-controllers are of three types, viz., hand-operated, 25 knee-operated and foot-operated. The hand-operated controller is little used as it interferes more or less with the use of the operator's hands in presenting and guiding the work to the sewing machines. The knee-operated controller is in more general favor, and there is practically no objection to the foot-operated controller in-so-far as the broad principle of foot-operation is concerned. Foot-controllers, such as heretofore commonly provided, have however been of the portable type comprising a pedal-operated rheostat adapted to rest upon the floor adjacent the sewing machine table. The difficulty with this type of foot-controller is that it has 30 a tendency to creep or shift its position. Furthermore, it cannot be placed in a position for convenient operation, for the reason that the treadle-plate element of the sewing machine table occupies the floor space where the foot-controller would be of most convenient access to the operator's foot and where it would be least likely to manifest its creeping tendency.

In the ordinary drop-head sewing machine, 35 as converted to an electric sewing machine

by the application of an electric motor and foot-controller, the treadle mechanism of the sewing machine stand has no function except as a potential foot-power drive and, as above stated, the treadle-plate is in the way of convenient location of the foot-controller. 55

With the idea of using the conveniently accessible and operable treadle-plate as a means for operating the motor-controller, it has been proposed to mount the motor-controller or rheostat on the sewing machine table and connect it by a pull-rod to the treadle-plate, but none of the devices heretofore proposed fills the long-felt want for a treadle-plate operated motor-controller which may be readily applied to or removed from the usual sewing machine table by one not possessed of mechanical skill, and which is of simple and dependable construction and of neat and inconspicuous appearance. 60 65 70

The present invention has for an object to provide a motor-controller to fill the want referred to and enable the well-known treadle-driven family sewing machine to be readily converted into an electric machine. 75 Further objects of the invention will appear in the following description and claims.

According to the present improvement the motor controller is in the form of a rheostat having an operating pull-rod with a straight or direct pull treadle-connection, avoiding the use of cams, levers, rock-shafts, etc., both within and outside of the rheostat casing, and reducing the operating mechanism to the simplest form. The rheostat is mounted within a casing one flat side face of which has secured thereto the concave side of a special longitudinally troughed bracket which clamps between it and said side face, an upwardly extending arm at a corner 80 85 90 of the central rectangular portion of the brace-member for the legs of the ordinary cast-iron sewing machine stand. The bracket is formed at its lower end with divergent legs extending beyond the casing and having feet 95 bent toward the plane of the side face of the rheostat casing and adapted to rest against the upper horizontal rib and one end-rib of the central rectangular member of the brace. 100

In the accompanying drawings, Fig. 1 is a front side elevation of the usual family sewing machine as converted to an electric machine in accordance with the invention. Fig. 2 is a rear side elevation of the motor-controller as mounted on the brace-member of the sewing machine stand; the controller-cover being removed. Fig. 3 is a section on the line 3—3, Fig. 1. Fig. 4 is a perspective 10 view of the bracket-member which cooperates with the controller casing to hold the controller clamped to the brace-member of the sewing machine stand. Fig. 5 is a central transverse vertical section through the sewing machine stand. Fig. 6 is a section on the line 6—6, Fig. 1. Fig. 7 is a detail view of the crank-strap or upper pitman-section used for foot-power drive. Fig. 8 is the rheostat pull-hook or second upper pitman-section used for electrical operation, and Fig. 9 is the lower pitman-section which is selectively connectible to either of the sections shown in Figs. 7 and 8.

Referring more particularly to Fig. 1, 1 represents the usual drop-head sewing machine table or stand having a wooden top 2 carrying the sewing head A. The top 2 is supported by the reticulated or ribbed cast-iron end legs 3 connected by an intermediate 25 ribbed cast-iron brace-member 4 pivotally carrying the usual reticulated treadle 5. The ribs of the brace-member 4 are shown in 4'. The brace-member is formed with a central rectangular portion 6 from the corners of which extend arms 7 secured to the legs 3. The brace-member 4 has mounted thereon and attached to the usual treadle-plate 5 a crank-shaft 8 carrying a belt-wheel 9 which, for foot-power operation, is connected by the belt 10, Fig. 1, to the usual grooved balance-wheel 11 of the sewing machine.

The crank-shaft 8 is embraced by the crank-strap 12 which, for foot-power operation is connected to the usual treadle-rod or pitman 13, as shown in Fig. 5; the crank-strap 12 constituting, in effect, an upper pitman-section or extension of the pitman 13. The pitman 13 has the usual ball-and-socket connection 14 with the treadle-plate 5 and is threaded at 15 at its upper end to screw into the threaded socket 16, Fig. 7, of the crank-strap 12.

For electrical operation, the belt is removed from the balance-wheel 9 and a motor 17, such for example as that shown in said Diehl and Hemleb patent, is applied to the sewing head and connected by a belt 18 to the balance-wheel 11. The motor 17 is connected to the source of electrical energy by the supply cord 19 in series with the cord 20 leading to the motor-controller 21 which, in the present instance, is a variable resistance device mounted on the brace-member 4 and including an operating pull-rod 22 to the apertured lower end of which is connected a hook 23

having the threaded socket 24, Fig. 8 for reception of the threaded end 15 of the pitman rod 13. As thus directly connected for electrical operation, pressure upon the treadle-plate 5 effects a downward sliding movement of the pull-rod 22, which effects a variation of the resistance in the motor circuit and enables the speed of the motor 17 and machine A to be nicely controlled.

The motor-controller comprises a base 25 from one end of which rises an end-wall 26 having a slot through which passes the pull-rod 22 connected at its inner end to the U-shaped member 27, the ends 28 of the legs of which are directed toward one another but spaced apart. Recovery-springs 29 serve to restore the pull-rod 22 to initial or non-running position with the ends 28 contacting with the stop-pins 30. The pull-rod 22 is formed with shoulders 22' which act as a stop by striking the end-wall 26 and limiting the motion of the pull-rod 22 in a direction to compress the springs 29.

Mounted on the base 25 independently of the pull-rod 22 and recovery-spring mechanism is the compression rheostat unit having the usual porcelain body 31 formed with spaced wells or chambers 32 for the stacks of carbon resistance disks 33 which substantially fill the wells 32 and are electrically connected to the terminals 34. The stacks 33 also comprise the compression heads 35 which are bridged by the bow-spring contact-member 36 backed by a stiffer spring-member 37 substantially in accordance with the disclosure of the patent to D. H. Chason, No. 1,643,292 of Sept. 27, 1927. From the center of the bow-spring 36 there extends in line with the pull-rod 22 a second pull-rod 38 having a screw-threaded end carrying an adjustable nut 39 whose shank passes through the space between the ends 28 of the U-shaped member 27. A recovery-spring 40 surrounding the rod 38 is disposed between the body 31 and the bow-spring 36. The nut 39 is so adjusted that the bow-spring will be carried out of contact with the pressure-heads 35 by the spring 40 when the springs 29 are holding the members 28 in engagement with the stops 30. The various parts on the base 25 are enclosed within a suitable casing 41.

The rheostat is secured to one of the arms 7 of the brace-member 4 by means of a special clamp having a trough-shaped body 42 formed at its upper end with oppositely extended arms 43 secured by screws to the flat side face of the rheostat base 25, so as to clamp the brace-member 7 to such base. The body 42 of the clamp is formed at its lower end with divergent legs 44 having feet 45 bent toward the plane of the base 25 so as to rest against the upper horizontal rib and one end rib of the central rectangular portion 6 of the brace 4.

By mounting the controller 21 on the brace 130

member 4, and particularly in rear of such brace-member, it is located in a position where its connection with the usual treadle-pitman may be effected with great simplicity.

5 Still further, it is not in a conspicuous position and, together with the cord 20, is well off of the floor and out of the way.

Having thus set forth the nature of the invention, what I claim herein is:—

10 1. A sewing machine motor-controller comprising a casing, a pull-rod extending through said casing, recovery-spring means in said casing connected to said pull-rod, co-acting stops associated with said pull-rod
 15 and casing and adapted to limit the in-and-out movement of the pull-rod, and a compression resistance unit mounted in said casing independently of said pull-rod, stops, and spring means, and including a second pull-
 20 rod connected to the first mentioned pull-rod.

2. The combination with a casing, a variable resistance unit housed in said casing and including a downwardly extending treadle-operated pull-rod, of a bracket secured to one side of said casing, said bracket having a longitudinally troughed body-portion adapted to clasp between it and said casing one of the upwardly extending arms 25 of the brace-member of the ordinary cast-iron sewing machine stand, said bracket also having diverging legs at the lower end of said body-portion, said legs having feet serving as rests in contact with the horizontal and 30 vertical edges of the rectangular central portion of said brace-member.

3. The combination with the brace-member for the legs of the ordinary cast-iron sewing machine stand, said brace-member having 35 an intermediate rectangular frame-portion and arms at the corners of said rectangular frame-portion, of a rheostat having a casing formed with a side face, a treadle-operated pull-rod controlling the rheostat, and a bracket having a longitudinally troughed body-portion embracing one of the arms of 40 said brace-member, means at one end of said body-portion securing said bracket to said rheostat casing side-face with the arm of 45 the brace-member clamped therebetween, said bracket having a pair of diverging legs at the other end of said body-portion, said legs extending beyond the rheostat casing and having feet resting against one horizontal 50 and one vertical edge of the rectangular frame-portion of said brace-member.

4. The combination with a sewing machine table having a treadle-plate, of a motor-controller comprising a compression resistance 55 unit and operating pull-rod, a direct-pull operating connection extending from said treadle plate to said operating pull-rod and a stop cooperating with an element of said operating connection for preventing the 60 transmission to said resistance unit of any

abnormal stresses accidentally applied to said treadle-plate.

5. The combination with a sewing machine table having a treadle-plate, of a motor-controller comprising a resistance-unit having 70 relatively delicate operating mechanism, a relatively strong direct-pull connection between said treadle-plate and said relatively weak resistance operating mechanism, and a stop cooperating with an element of said 75 relatively strong direct-pull connection to safely take any abnormal strains applied to the treadle and prevent transmission of such strains to the resistance unit.

In testimony whereof, I have signed my 80 name to this specification.

DANIEL H. CHASON.
